VENDING MACHINE

Samuel Brill and Clifford C. F. Clarke,
Toronto, Ontario, CanadaApplication August 27, 1938, Serial No. 227,104
In Canada August 28, 1937

2 Claims. (Cl. 194—73)

This invention appertains to vending machines, and more particularly to coin-actuated machines for vending lead pencils and the like, and the objects of the invention are: (1) to vend one or more lead pencils at a time by means of an inexpensive coin-actuated mechanism of positive action; (2) to insure that the operating plunger designed to be pushed in by the purchaser after inserting a coin in the machine will positively actuate mechanism to discharge one or more pencils, as the case may be; (3) to insure that the coin cage will be positively returned to its normal position out of contact with the operating plunger after a pencil has been discharged from the machine so that only one pencil, as the case may be, can be obtained for one coin; (4) to hold the operating plunger in positive engagement with the coin cage as the said plunger is pushed in to insure the discharge 20 of a pencil from the machine, and (5) to permanently attach the operating mechanism of this machine to a back-wall to make the same a fixed unit therewith and attach this unit permanently to a wall or other support so that the case enclosing said mechanism may be readily uncoupled therefrom to permit replenishing of supplies, and thus obviate any possibility of the operating parts being injured through being accidentally dropped on the floor.

Broadly considered, the invention comprises a carrier frame mounted to have horizontal movement on suitable supporting means carried by one or more supporting bars. The carrier frame is spring-controlled and is constructed to receive one or more pencils from fixed hoppers located in spaced relation thereabove, means being provided to move said carrier frame to dislodge the pencil resting upon one of said supporting bars to ultimately cause it to be discharged from the machine. A spring-provided plunger is associated with a coin cage, which is adapted to have its center of gravity changed when a coin is held thereby, means being provided when said plunger is operated to dislodge said coin from its cage and to operate means to move said carrier frame, for the purpose stated.

Fig. 1 is a front elevation of the machine on a reduced scale as it appears with the casing in place. Fig. 2 is a front elevation, on an enlarged scale, of the operating parts of the machine. Fig. 3 is a vertical section on the line 3—3, Fig. 2. Fig. 4 is a plan view of the operating plunger and the coin cage, in normal position, with supporting bars. Fig. 5 is a section 55 on the line 5—5, Fig. 3, particularly through the

coin cage. Fig. 6 is a vertical section on the line 6—6, Fig. 1, through the part of the coin-receiving chute carried by the casing. Fig. 7 illustrates detail views in elevation of the inner end of the operating plunger, and Fig. 8 is a detail view, partly in section, showing in side elevation a portion of the lever for conveying motion to the ejector-frame suitably formed to insure positive engagement therewith of the coin cage plate.

In the drawings, like characters of reference refer to the same parts.

2 is the back-wall of the machine, and it is provided at top and bottom with battens 3 attached thereto by any suitable means. This back wall is permanently attached to any suitable support such as the wall 4 of a room. Attached to the back wall 2 are the operating parts of the machine hereinafter described in detail. These operating parts are enclosed in a casing 20 composed of a front wall 6, side walls 7, top 8, and a bottom 9. The top portion 5 of the top batten 3 is rebated leaving a space between this top portion and the wall 4 to receive the flange 10 of the said casing. When the casing is placed in position the flange 10 is passed into the said space, and then the bottom 9 is placed with its flange 11 against the bottom batten. In the lower portion of the wall 6 is formed an aperture 12 through which access is had to the bottom of said casing. This aperture is formed by partially cutting the said front wall and bending the cut portion of said wall inwardly thus forming a deflecting plate 13. Associated with the bottom 9 is a chute 14 which is in length somewhat longer than the aperture 12. A plate abuts against each end of the said chute, one of these plates being shown at 15 in Fig. 3. 16 is any suitable lock attached to the lower portion of the wall 2, and access is had thereto through the aperture 12 as well as through the opening 17 formed in the chute 14. When the casing has been positioned as described, and clearly shown in Fig. 3, a bolt 18 of the lock is moved to rest against the inner side of the flange 11, thus locking the casing to the back wall 2.

Vertically formed in the wall 6 is an aperture 19, and this aperture is closed by any suitable transparent material 20, such as glass. The article vended will be visible through said aperture.

The rebated portion 5 is so formed that after unlocking the casing, when the bottom part thereof is pulled away from the back wall 2, the casing will pivot around the flange 10 to permit 55

the casing to be disengaged. While the construction of the casing has been particularly described, it must be understood that any suitable type of casing may be used and that the claims 5 are not to be construed as limited to the said construction.

This machine can be constructed to vend simultaneously one or more articles, though it is limited as constructed to vend at most two articles. 21 are vertical chutes U-shaped in horizontal section, and in vending pencils and the like these chutes are located in pairs spaced apart as shown clearly in Fig. 2. 22 are vertical plates suitably tied together at their lower portions by means of supporting bars 23 which rest upon brackets 24. The plates 22 are attached to their associated chutes 21 by plates 25. These plates are in turn suitably coupled to the back wall 2, by means of brackets 26. Each pair of chutes form what might be termed a hopper.

As illustrated in Fig. 3, there are two pairs of hoppers, and when two pairs are used these may be tied together by tie bars 27. The lower tie bar 27 may be suitably supported from the plates 22, 25 as by means of the brackets 28. 29 is a tie bar coupling together the lower ends of the vertical chutes forming the rear hopper.

Located underneath the chutes 21 in spaced relation thereto is a carrier frame, which, when two pairs of chutes are used, is composed of three horizontal spaced-bars 30 located in the same plane. These bars extend between the plates 22 and are tied together at each end by plates 31 which have movement longitudinally of the brackets 32 which are secured to the supporting bars 23. These brackets are attached at their inner ends 33 to the back wall 2. At each side of the machine is a spring housing 34 in which is housed a coiled spring 35. The inner end of 40 each spring is suitably secured to its associated housing, and the outer end of each spring is suitably secured to a vertical plate 36 forming part of each bracket 32. Each spring housing is attached to the bars 30, and slides underneath a bracket 37 attached to each plate 22. 38 is a rock-shaft suitably supported by the plates 22. Mounted on and suitably secured to said rock-shaft are slotted levers 39. Extending through the slot of each lever is a stud 40. Each of these 50 studs is suitably secured to the top side of its associated spring housing 34. The end 41 of the rock-shaft projects beyond its associated plate 22 and suitably keyed on this end is a lever 42 which normally occupies a vertical position. 43 55 is a plunger which projects through the front wall of the casing (see Fig. 1) and also through the front wall 44 of the frame that supports the operating parts immediately associated with the coin cage. This frame in addition to the said 60 front wall 44, consists of a side wall 45 and a rear wall 46 which is suitably attached to the back wall 2. The walls 44 and 46 are also attached to the associated wall 22 as shown clearly in Figs. 2 and 4. The inner end of the plunger 65 rests in a slot 47 formed in the back wall 2, and it will be noted upon referring particularly to Fig. 2, that the said plunger is located between the associated wall 22 and the lever 42. Carried by the said plunger is a collar 48 the normal position of which is in contact with the inner side of the wall 44. 49 is a coiled spring mounted on the plunger 43, the same is held between the wall 46 and the clamp 50 mounted on said plunger. This spring returns the plunger to normal position, and the collar 48 limits the outward move-

ment of said plunger by contact with the wall 44. 51 is a rod suitably supported by the walls 44 and 46. The coin cage 52 is mounted on this rod by means of the ears 53 carried by the plate 54 of said cage. 55 is a coiled spring mounted on the rod 51 between the collar secured at the inner end of said rod and the inner ear 53. The function of this spring is to insure the return of the coin cage to normal position underneath the coin chute, with one of these ears 53 more or less in contact with a collar 56 mounted on the rod 51.

The coin cage is without a top and is composed of side walls 57 and end walls 58. One of said side walls is provided with an inturned deflecting plate 59 which is spaced apart from the deflecting plate 60 of the other side wall, the latter deflecting plate extending considerably below the plate 59. Each end wall 58 is formed to extend inwardly towards each other to form flanges 61 to retain the coin.

When a coin is passed through the slot 62 formed in the front wall 6 of the casing, it passes into a chute 63 carried by said front wall and in its downward passage strikes against a deflecting plate 64 located below said chute and suitably carried by said front wall. This deflecting plate 64 (see Figs. 2 and 6) directs the coin into the mouth 65 of the chute 66 with the result that as the coin passes from said chute it passes between the walls 57 of the coin cage and is deflected by the plate 59 against the plate 60 and between the flanges 61 where it lodges. In the normal position of the coin cage the weight 67 keeps the coin cage in the position shown in full lines in Fig. 2 so that it will be in position to receive a coin. In other words, the weighted end of the plate 54 overbalances the rest of this plate and the coin cage. But when the weight of the coin is added to that of the said coin cage and its immediate associated portion of the plate 54, this cage and its plate are moved around the rod 51 into the position shown by dotted lines in Fig. 2. In this position the weighted end of the plate 54 is moved into the path of movement of the 45 collar 48 of the plunger 43. When this plunger is pushed inwardly said collar will engage with said plate 54 and move this plate and the coin cage along the rod 51 compressing the spring 55. Movement of the coin cage 52 is far enough to bring the coin into contact with the push bar 68 with the result that the coin is dislodged from between the flanges 61 and drops to the bottom of the casing. When the plate 54 is being moved inwardly as described it will come in contact with the lever 42 with the result that the rock-shaft 38 will be moved, thus moving the spring housing 34 and carrier frame composed of the bars 30 inwardly elongating the springs 35. Before the movement just described takes place, a lead pencil 69 has dropped from the vertical chute 21 above the same on to one of the supporting bars 23 where it rests between two of the bars 30. As the carrier frame is moved backwardly through the movement of the spring 65 housings 34, the pencil 69 is moved to finally pass into the dotted position shown in Fig. 3 between the supporting bars 23 to finally drop on to the deflecting plate 13 then on to the chute 14 to finally come to rest in contact with the 70 flange a forming part of the bottom 9. In this position, the pencil can be removed from the aperture 12.

In order to insure that the coin cage will be positively returned to normal position, the side 75

of the lever 42 engaged by the plate 54 is notched. When the lever 42 starts to be moved back to normal position one of the notches thereof in contact with the plate 54 will press downwardly upon the said plate as it is being moved outwardly and thus exert a thrust to move the said coin cage back to normal position. This return movement of the lever 42 is of course caused by the springs 35. In order to positively prevent any manipulation of the plunger 43 so as to secure more pencils than paid for, the movement of the associated parts just described is so timed that shortly after the plunger starts to return to normal position through the action of the spring 49, the side of the plate 54 in engagement with the lever 42 becomes quickly disengaged therefrom with the result that the carrier frame composed of the bars 30 is shot back to normal position and so that there will be no possibility of the plunger 43 being gradually permitted to return to normal position with the plate 54 in contact with the lever 42, and then moved inwardly again to obtain more pencils than have been paid for.

Obviously the chutes 21 will be filled with pencils, and when a bar 30 is moved thereunder passage of a pencil from said chutes will be prevented by said bars, and when said bars assume the positions shown in Fig. 3 a pencil will drop into each of the slots between the said bars 30 and rest upon their associated supporting bars 23.

Where two pencils are vended simultaneously, obviously the pencil passing through the slot c (Fig. 3) will be ultimately discharged into the bottom of the machine over the rear side of the supporting bar 23 at the right-hand side of Fig. 3.

As the coin cage and its plate 54 are moved inwardly with the edge of this plate in contact with the toothed side of the lever 42 this lever would act to move downwardly the plate in contact therewith thus elevating the coin cage and the coin carried thereby unless prevented so doing. To prevent this downward movement the inner face of the collar 48 is toothed and will simultaneously engage with its associated side of the plate 54 as shown in Fig. 7 thus positively holding the said plate and its associated coin cage in position shown in dotted lines in Fig. 2. While the plate 54 is so held, during its inward movement, it will obviously slide over one or more of the teeth formed on the lever 42, but will not when said inward movement ceases be out of contact with the said lever to insure the return of the coin cage back to normal position, after the plunger 43 has been released.

The push bar 68, as shown clearly in Fig. 2, is directly in the path of movement of the coin, and will positively dislodge the same from the coin cage. It is preferred to make this push bar more or less resilient in character so that in case a deformed or "doctored" coin should be passed into the coin cage the said push bar will yield but yet maintain sufficient contact with the coin to insure its dislodgment.

The preferred push bar consists of a coiled spring supported on a bar b, suitably carried by the back wall 2.

It must be understood that a push bar made of a stiff rod may be employed if desired.

While the coiled spring 55 is shown, this may be dispensed with since it is found in practice that the springs 35 when quickly returning the lever 42 and associated parts back to normal position will also, through contact of said lever against the plate 54 quickly force this plate outwardly to permit the coin cage to assume nor-

mal position. The advantage of the spring 55 resides in the fact that it will positively remove the associated side of the plate 54 out of contact with the lever 42 and hold it out of contact so that this lever cannot prevent the return to normal position of the coin cage.

The upward movement of the plate 54 when it occupies the position shown in Fig. 2 in dotted lines is limited by contact with the portion of the plunger behind the wall 44 beyond the collar 48. In this position the said plate is positively in the path of movement of said collar.

The clearance separating the top sides of the bars of the carrier frame from the extreme lower ends of the chutes 21 is sufficiently less than the transverse diameter of the article vended so that, for example, when the pencil 69 is being moved into the slot between the supporting bars 23 the lowermost pencil in the front pair of chutes 21 will ride upon the top of the left-hand bar 30, 20 and when the said carrier frame is returning to normal position the pencil extending partly into the said vertical chutes will ultimately drop into the slot containing the pencil 69 in Fig. 3 when this slot moves into alignment therewith. Thus it will be seen that the pencil extending partly into chutes 21 and resting upon one of the bars 30 acts as a check against the downward movement of the column of pencils above it.

The side 45 acts as a stop to limit upward movement of the coin cage.

What we claim as our invention is:

1. In a machine of the class described, in combination a suitable frame; a spring-controlled plunger having movement in said frame; a rod 35 held in said frame substantially parallel to said plunger and in spaced relation thereto a coiled spring slidably mounted on said rod; a coin-cage pivotally and slidably mounted on said rod and against which cage said spring constantly 40 presses to keep it in forward position, a plate carried by said coin-cage of sufficient weight to overbalance this latter when empty to hold it in position to receive a coin, and lying underneath said plunger, the said coin-cage when holding a 45 coin moving downwardly to overbalance said plate and move it into contact with said plunger, a collar carried by said plunger and toothed on its inner end and of greater diameter than said plunger and adapted to engage said plate resting 50 against said plunger when this latter is moved inward and thereby move said coin-cage inwardly on its supporting rod and means carried by said frame adapted to displace said coin from said coin-cage as this latter is moved inwardly.

2. In a machine of the class described, in combination, a holder for the article to be vended; a suitable supporting frame; a fixed horizontal bar located below the discharge end of said holder and in spaced relation thereto and adapted to act as a rest for the article dropped thereupon; a spring-held horizontally-operated slotted member interposed between said holder and said fixed bar; a manually-operated spring-controlled 65 plunger having movement in said frame; a rod held in said frame substantially parallel to said plunger and in spaced relation thereto; a coiled spring slidably mounted on said rod; a coin chute carried by said frame; a coin cage pivotally and 70 slidably mounted on said rod and in co-operative position in respect of the discharge end of said coin chute, and against which cage said spring constantly presses to keep it in forward position; a plate carried by said coin cage of suffi- 75

cient weight to overbalance this latter when empty to hold it in position to receive a coin from said chute, and lying underneath said plunger, the said coin cage when holding a coin moving downwardly to overbalance said plate and move it into contact with said plunger; a collar carried by said plunger and toothed on its inner end and of greater diameter than said plunger and adapted to engage said plate resting against said plunger when this latter is moved inward and thereby move said coin cage inwardly upon its supporting rod; means carried by said frame adapted to displace said coin

from said cage as this latter is moved inwardly; a horizontal rod carried by said frame; a toothed lever carried by said rod and depending therebelow and adapted to be moved by said plate as this latter is moved inwardly to move said rod on its longitudinal axis, and means actuated by said rod to move said slotted member to dislodge the article resting on said horizontal bar and at the same time cause said slotted member to move beneath the discharge end of said holder to prevent the escape of an article therefrom.

SAMUEL BRILL.

CLIFFORD C. F. CLARKE.
